BABY BOTTLE WARMER

Ivar Jepson, Oak Park, Ill., assignor to Sunbeam Corporation, Chicago, Ill., a corporation of Illinois

Application November 17, 1951, Serial No. 17,459

Term of patent 14 years

(Cl. D81—10)

To all whom it may concern:

Be it known that I, Ivar Jepson, a citizen of the United States, residing at Oak Park, in the county of Cook and State of Illinois, have invented a new, original, and ornamental Design for Baby Bottle Warmer, of which the following is a specification, reference being had to the accompanying drawing forming a part thereof, in which:

Fig. 1 is a perspective view of a baby bottle warmer embodying my new design;

Fig. 2 is an elevational view of the baby bottle warmer shown in Fig. 1.

Fig. 3 is a top plan view of the baby bottle warmer shown in Figs. 1 and 2.

The side of the baby bottle warmer not visible in Fig. 2 is substantially similar to the side shown except for the control knob and the opening therefor.

I claim:

The ornamental design for a baby bottle warmer, substantially as shown and described.

IVAR JEPSON.
